FROSTPROOF HYDRANT

Joseph A. Vogel, Wilmington, Del.

Application October 5, 1936, Serial No. 104,122

10 Claims. (Cl. 137—13)

This invention relates to improvements in frost-proof hydrants, drinking fountains, wash sinks and other like water service apparatus of that type embodying a stand pipe having a discharge nozzle and a valve movable to a position for admitting water from a source of supply to the stand pipe for discharge through the nozzle and to a position for cutting off the supply of water to the stand pipe and connecting the stand pipe with a drain outlet for the drainage of water from the stand pipe after each water supply action. The combined water supply and drain valve referred to is carried by a rod or stem which extends upwardly through the stand pipe and is adapted to be raised by a handle or operating device to open the valve for a water supply action and to be lowered to return the valve to normally closed position in which it cuts off the supply of water and simultaneously connects the stand pipe with the drain outlet. The movement of the valve to open position in this type of apparatus results in a full or maximum flow of water through the nozzle, no provision being made for securing a graduated or regulated flow.

It is desirable in some uses of a frostproof hydrant to secure a graduated or regulated discharge of the water without interfering with the normal operation of the hydrant for securing a full flow action and also without endangering its frostproof properties.

One object of my invention is to provide a construction of frostproof hydrant whereby a full flow or partial or regulated flow may be secured at will.

Another object of my invention is to provide means whereby the valve mechanism may be operated in the usual manner for a full flow action and in a different manner for a desired reduced flow action.

Still another object of the invention is to provide a means whereby an ordinary hydrant valve mechanism may be readily modified to secure a regulated flow action without material departure from a commonly used frostproof valve structure of efficient type.

Still another object of the invention is to provide a valve mechanism which gives visual indication of the position of the combination valve in the event that it is not closed after a flow action, so as to avoid any liability of the valve being left open and of the hydrant being left to freeze in freezing weather.

The invention consists of the features of construction, combination and arrangement of parts, hereinafter fully described and claimed, reference

being had to the accompanying drawings, in which:

Fig. 1 is a view, partly in side elevation and partly in section, of a frostproof hydrant embodying my invention.

Fig. 2 is a sectional view through the hydrant showing the parts in normal position or with the water inlet closed and drain valve open.

Fig. 3 is a similar view with the valve mechanism adjusted for a full flow action and to allow of a reduced or graduated flow action.

Fig. 4 is a detail section on line 4—4 of Fig. 3.

Figs. 5 and 6 are sections on the line 5—5 of Fig. 3 showing the graduated flow valve in partially closed and fully opened positions respectively.

Fig. 7 is a vertical section through the upper part of the hydrant showing a modified construction of the graduated flow valve.

Figs. 8 and 9 are sections on lines 8—8 and 9—9 of Fig. 7, looking respectively downward and upward.

In the illustrated embodiment of the invention, I have, for purpose of exemplification, shown the same in application to a Vogel frostproof type of hydrant, but it is to be understood that the invention is not limited in application in this respect, as it may be used with similar advantages in connection with frostproof drinking fountains, wash sinks and other water service apparatus for which it is or may be adapted.

Referring now more particularly to the drawings, 1 designates a stand pipe which is connected at its lower end with a water service or supply pipe 2 and is provided near its upper end with a water discharge outlet, herein shown in the form of a discharge nozzle 3. Adjacent its lower end, and at a suitable elevation above the pipe 2, the stand pipe 1 is also provided with an outlet 4 for connection with a drain pipe 5. The drain outlet 4 communicates with the upper portion of a part or section 6 of the pipe 1 which serves as a valve chamber, in which is arranged a vertically movable combined water inlet and drain valve 7. This valve 7 comprises a lower valve member 8 controlling the inlet of water from the pipe 2 and an upper valve member 9 controlling the drain outlet 4. The valve member 9 is hollow or of openwork construction and provided above and below the plane of its seat surface with ports 10 and 11 to allow water to flow between the pipe 1 above the level of the drain of the drain valve and the drain outlet or the water inlet 2 in the different positions of the valve members 8 and 9.

The valve 7 is connected to the lower end of the main section of a rod or stem 12 extending upwardly through the pipe 1 to a point substantially in line with the lower end of an outlet chamber 13 attached to the upper end of the pipe 1, which chamber serves as an auxiliary valve chamber and has formed thereon or attached thereto the discharge nozzle 3. The upper end of this chamber 13, which projects above the nozzle, is closed by a stuffing box 14 provided with a gland or follower 15 clamping suitable packing 16 in place. An upper or operating rod section 17 is disposed within the outlet chamber and extends at its upper end outwardly through the stuffing box. The lower end of this rod section 17 is connected to the upper end of the main rod 12 by a threaded sleeve coupling 18, while the upper, outwardly projecting end of said rod section 17 carries an operating handle or lever 19, whereby the rod as a whole may be raised and lowered to operate the valve 7. A coiled spring 20 disposed about the rod section 17 between the coupling 18 and the top of the stuffing box or a thimble 21 bearing thereon serves to hold the rod normally depressed and the valve 7 in water cut off position. The handle or lever 19 has a forked or slotted head portion 22 receiving a cap 23 threaded onto the upper end of the rod section 17, through which rod section, cap and the side walls of the slot of the head 22 passes a pin or bolt 24 pivotally mounting the handle on the upper end of the valve rod. The head 22 is so pivoted or shaped for engagement with the gland 15 as to serve as a lifting cam operating when the handle 19 is swung on its pivot from a normally vertical position to a horizontal position to lift the rod against the resistance of the spring 20 and thereby raise the valve 7 from water cut out to water let on position, in which action the upper end of the rod section 17 and cap 23 move in the slot of the head 22. In the upward movement of the valve 7 the drain outlet 4 is closed and communication between the stand pipe and supply pipe 2 established for the flow of water in full volume to the nozzle 3. When the handle 19 is shifted back to its normally vertical position the rod is depressed by the action of the spring 20, the valve 7 being thereby returned to normal position to cut off the flow of water from the pipe 2 and to open communication between the stand pipe and drain outlet 4 for the discharge of all residual water remaining in the stand pipe above the valve 7. In practice the water supply connections to the stand pipe are arranged below the frost line, and this drainage action ensures that no residual water from a supply action is allowed to remain in the stand pipe to freeze in freezing weather.

A disadvantage applying to water service apparatus of this character is that when the valve 7 is opened a full volume discharge of water from the nozzle 3 always occurs. At times and in certain uses of the apparatus, as when it is desired to secure the discharge of water in small or varying volume, this is objectionable not only on account of the waste of water but for many other obvious reasons. In order to avoid this objection I provide means whereby after opening of the valve 7 the discharge of water from the nozzle 3 may be reduced and graduatively controlled, which means is of such construction that it does not interfere with or impair the frostproof control action of the valve mechanism. To this end I provide auxiliary valve means operative by rotation of the valve rod or stem when the valve 7

is open for controlling the discharge of water through the nozzle 3.

In Figs. 1 to 6, inclusive, I have shown one form of auxiliary valve means for this purpose in which the chamber 13 is provided with a projection or inwardly extending offset 25 and a port 26 defined thereby, which port connects said chamber with the inlet end of the nozzle. For cooperation with said port an auxiliary valve is provided comprising wing like segmental shaped flanges 27 on the coupling 18. These flanges are so shaped as to form between them flow passages 28; and each flange 27 is so accurately formed for coaction with the port 26 that when disposed beneath said port and turned in either direction it will form a passage of variable size between the chamber and port to graduatively control the flow of water therefrom to the nozzle, while when either passage 28 is disposed in register with the port a full flow of water to the nozzle is allowed. In the normal position of the parts one of the valve wings is centrally disposed beneath the port 26 and spaced such a distance therefrom that when the handle 19 is operated to lift the valve 7 to open position the said valve wing will be brought close to but not in full closing relation to the port. By this means the flow of water to the nozzle will be reduced to a minimum service degree but not entirely cut off. By rotation of the handle 19, in the horizontal position to which it has been moved in lifting the valve 7, the valve stem may be turned to the right or left to adjust the acting valve wing to vary the extent of its obstructing surface relative to the port 26, whereby the discharge of water through the nozzle may be reduced for any particular service purpose.

In the construction shown in Figs. 7, 8 and 9 the outlet chamber 13a has fitted therein a stuffing box 14a which is flanged at its top for the engagement therewith of a flanged clamping ring 29 threaded onto the casing and whereby the stuffing box is held from outward displacement. This stuffing box conforms generally, so far as its packing features are concerned, with the structure shown in Figs. 1 to 6, inclusive, and its similar parts are correspondingly numbered. This box 14a, however, is formed with a depending shell 30 provided in its side with a port 31 facing the nozzle and having an annular bottom wall 32 formed with sets of valve ports 33. The coupling member 18a in this construction has a circular flange or valve disk 34 provided with arcuate slots 35 for cooperation with the sets of ports 33 to secure a graduative discharge action. The shell 30 may be provided with a spline or key projection 36 to engage a seat groove 37 in the casing for holding the shell from rotation and ensuring accurate positioning of the valve ports 33. The operation with this construction is the same as that described with respect to the construction shown in Figs. 1 to 6, inclusive, for the purpose of obtaining a graduative discharge of the water.

In both forms of the auxiliary valve means disclosed the construction and range of movement of the auxiliary valve member on the rod toward the stationary valve member in the auxiliary valve casing is such that in the maximum closing position of the valve members the port or passage leading from said valve casing to the nozzle is not fully closed, sufficient space being left for flow of a predetermined amount of water

to the nozzle as long as valve 1 is open and in the fullest flow obstructing position of the auxiliary valve. Thus in the event that the handle should not be returned to normal position after a discharge action, that fact will be visually indicated by the flow of a small amount of water from the nozzle, ensuring attention being given to cut off the flow by returning valve 1 to closed position for a drain action and to prevent freezing of the hydrant during freezing weather. My invention thus provides in addition to its advantageous features described a simple safeguard against the valve 1 being left open through oversight after use of the hydrant, whereby the frostproof property of the hydrant structure is maintained and preserved.

From the foregoing description, taken in connection with the drawings, the construction, mode of operation and advantages of my invention will be readily understood, and it will be seen that the invention provides a frostproof hydrant or other frostproof water service apparatus whereby either a full or graduative discharge of water from the discharge nozzle may be secured at will and by the provision of a simple and efficient type of means for the purpose. Also it will be seen that the invention provides auxiliary valve means for a graduative water discharge action which may be employed without interfering with the normal operation of the hydrant and without endangering its frostproof properties. It will further be seen that the invention provides auxiliary means for a graduative flow discharge action which may be applied to and employed in conjunction with the parts of an ordinary hydrant valve mechanism and without material departure from approved types of frostproof hydrant or like water service structure. While the construction is such that the customary return of the operating handle to normal position after a water supplying action ensures that the main valve will be returned to water cut off and drain position, the invention further safeguards the apparatus against liability of freezing by providing a means for indicating whether or not the main valve has been returned to cut off position, thus enabling measures to be taken to prevent freezing in case that through carelessness or inattention on the part of the operator the operating handle should be left in valve opening position.

It will, of course, be understood that while I have shown certain embodiments of my invention for purposes of exemplification, changes in the form, details of construction and arrangement of parts may be made within the scope of the appended claims without departing from the spirit or sacrificing any of the advantages of the invention.

60 What I claim is:—

1. In a frostproof hydrant, the combination of a stand pipe having a water inlet and a drain outlet at its lower end and a discharge nozzle at its upper end, an inlet valve in said pipe movable upwardly to a position in which it opens communication between the inlet and stand pipe for a full flow of water to the nozzle and closes communication between the drain outlet and stand pipe and downwardly to a position in which it closes the inlet and opens communication between the drain outlet and stand pipe, means for operating said valve, and a discharge regulating valve movable with the inlet valve in its upward and downward movement into and out of operative relationship to the discharge nozzle,

nozzle and operative by said operating means in the open position of said inlet valve for graduatively regulating the discharge of water through the nozzle.

2. In a frostproof hydrant, the combination of a stand pipe having a water inlet and a drain outlet at its lower end and a discharge nozzle at its upper end, a water inlet valve in said pipe movable upwardly to a position in which it opens communication between the inlet and stand pipe for a full flow of water to the nozzle and closes communication between the drain outlet and stand pipe and downwardly to a position in which it closes the inlet and opens communication between the drain outlet and stand pipe, means movable in a certain general direction for opening and closing the water inlet valve, and a valve movable with the inlet valve on its upward and downward movements into and out of operative relationship to the discharge nozzle for regulating the discharge of water from the nozzle in the open position of the inlet valve, said regulating valve being operable by movement of the aforesaid means in a different general direction from the first-named general direction for graduatively regulating the discharge of water through the nozzle.

3. In a frostproof hydrant, the combination of a stand pipe having a water inlet and a drain outlet at its lower end and a discharge nozzle at its upper end, a valve in said pipe movable upwardly to a position in which it opens communication between the inlet and stand pipe for a full flow of water to the nozzle and closes communication between the drain outlet and stand pipe and downwardly to a position in which it closes the inlet and opens communication between the drain outlet and stand pipe, valve governing means movable in a vertical direction for opening and closing the valve, said means being also movable in a horizontal direction, and regulating valve means including a member movable with the inlet valve in its upward and downward movements into and out of operative relationship to the discharge nozzle and operable by movement of the valve governing means in a horizontal direction for graduatively regulating the discharge of water through the nozzle.

4. In a frostproof hydrant, the combination of a stand pipe having a water inlet and a drain outlet at its lower end and a discharge nozzle at its upper end, a water inlet valve in said pipe movable upwardly to a position in which it opens communication between the inlet and stand pipe for a full flow of water to the nozzle and closes communication between the drain outlet and stand pipe and downwardly to a position in which it closes the inlet and opens communication between the drain outlet and stand pipe, a member moving in a rectilinear path for opening and closing the valve, said member being also movable in a rotary path, a rotary discharge regulating valve movable with the inlet valve in its upward and downward movements into and out of operative relationship to the discharge nozzle and operable by movement of said member in a rotary path when the water inlet valve is in open position for graduatively regulating the discharge of water through the nozzle, and means for imparting such movements to said member.

5. In a frostproof hydrant, the combination of a stand pipe having a water inlet and a drain outlet at its lower end and a discharge nozzle at its upper end, a water inlet valve in said pipe movable upwardly to a position in which it opens

- communication between the inlet and stand pipe for a full flow of water to the nozzle and closes communication between the drain outlet and stand pipe and downwardly to a position in which it closes the inlet and opens communication between the drain outlet and stand pipe, a rod movable in a rectilinear path for opening and closing the water inlet valve, said rod also being rotatable, a rotary discharge regulating valve movable with the inlet valve in its upward and downward movements into and out of operative relationship to the discharge nozzle and operable by rotation of said rod when the water inlet valve is in open position for graduatively regulating the discharge of water through said nozzle, and means for imparting such movements to said rod.
6. In a hydrant, the combination of a stand pipe having a water inlet at its lower end and a water discharge nozzle at its upper end, said water discharge nozzle having a horizontal inlet end, a reciprocating water inlet located within the stand pipe valve controlling said water inlet, a vertically movable and rotatable rod connected to the water inlet valve, the said water inlet valve being movable through up and down vertical movements of the rod to open and closed positions, a discharge regulating valve connected to the rod and movable thereby in the upward and downward movements thereof into and out of operative relationship with respect to said inlet end of the nozzle, said regulating valve being rotatable across the inlet of the nozzle by rotation of the rod when the water inlet valve is in open position for graduatively regulating the discharge of water through the nozzle, and means for vertically moving and rotating the rod.
7. In a hydrant, the combination of a stand pipe having a water inlet at its lower end and a water discharge nozzle at its upper end, an inlet valve member controlling said inlet, a vertically movable and rotatable rod connected to the valve, the valve being movable through up and down vertical movements of the rod to open and closed positions, a discharge regulating rotary valve member vertically movable into and out of operative position with relation to the nozzle by the up and down movements of said rod and operable by rotation of the rod when the inlet valve member is in open position for graduatively regulating the discharge of water through the nozzle, and a cam member having an operating handle, said cam member being pivoted to the rod and engageable with the stand pipe for rod raising and lowering movements and operative for rotating said rod.
8. In a frostproof hydrant, the combination of a stand pipe having a water inlet and a drain outlet at its lower end and a discharge nozzle at its upper end, a reciprocating water inlet valve in said pipe movable upwardly to a position in which it opens communication between the inlet and stand pipe for a full flow of water to the nozzle and closes communication between the drain outlet and stand pipe and downwardly to a position in which it closes the inlet and opens communication between the drain outlet and stand pipe, means for operating said valve, and a rotary auxiliary valve movable with the water inlet valve in its upward and downward movements into and out of operative relationship to the discharge nozzle and operable by said operating means in the open position of the first-named valve for graduatively regulating the discharge of water through the nozzle.
9. In a hydrant, the combination of a stand pipe having a water inlet at its lower end and a water discharge nozzle at its upper end, a vertically movable valve controlling said inlet, a vertically movable and rotatable rod connected to the water inlet valve and movable upwardly to open the valve and downwardly to close the valve, a valve member movable upwardly and downwardly with the rod into and out of operative relationship to the discharge nozzle and movable in the open position of the water inlet valve by rotation of the rod to graduatively control the discharge of water through the nozzle, and means for vertically moving and rotating the rod.
10. In a hydrant, the combination of a stand pipe having a water inlet and a drain outlet at its lower end and a discharge nozzle at its upper end, a reciprocating main valve movable upwardly to a position to open communication between the inlet and stand pipe and close communication between the drain outlet and stand pipe and downwardly to a position to close communication between the inlet and stand pipe and open communication between the drain outlet and stand pipe, a vertically movable rod for operating said main valve, said rod also being rotatable, a rotary auxiliary valve coupled to the rod for movement therewith, said auxiliary valve being movable upwardly and downwardly into and out of operative relation to the discharge nozzle by the upward and downward movements of the rod in the opening and closing movements of the main valve thereby, and said auxiliary valve being movable in the open position of the main valve by rotation of the rod to graduatively control the discharge of water through the nozzle, and means for vertically moving and rotating the rod.

JOSEPH A. VOGEL.
